UNITED STATES PATENT OFFICE

2,443,937

DEVICE FOR SHARPENING HYPODERMIC NEEDLES

Robert L. Torteson, Auburn, Mass.

Application May 9, 1947, Serial No. 747,048

2 Claims. (Cl. 51—217)

1

This invention relates to new and improved means for sharpening hypodermic needles and includes means for holding the needle with its free or penetrating end adjacent a precision-made grinding or honing surface at an angle to the axis of the needle so as to sharpen the needle at the optimum penetrating angle, having regard to the strength of the hypodermic needle.

It is well known by users of hypodermic needles that they quickly become dull and curl up forming a hook, this hook being very painful to the user and capable of forming infections and bruises in the skin, and it is a primary object of this invention to provide a relatively simple, pocket size sharpener which may be used by anyone and which will sharpen the needle effectively at the proper angle so as to provide a penetrating point which is clean and sharp and which will not form the above described hook in use.

Further objects of the invention include the provision of a precision pocket device for sharpening hypodermic needles comprising a holder which is open at one end and is hollowed out for a major portion of its length, said holder terminating at its closed end in an inclined grinding or stone guiding surface of the proper angle, there being a small passage intersecting this surface and communicating with the hollow portion of the holder for reception of the hypodermic needle so as to locate the penetrating end thereof at said surface for grinding and honing the same at the proper angle; and including a rod insertable in the hollow holder, said rod being provided with friction means holding the same where manually positioned and including at the inner end thereof a tapered projection on which the hypodermic needle may be located for insertion of the latter in the holder so as to position the needle in the above described passage.

Other objects and advantages of the invention will appear hereinafter.

Reference is to be had to the accompanying drawings in which

Fig. 1 is a view in side elevation of the device showing the same in use;

Fig. 2 is a top plan view of the device;

Fig. 3 is a greatly enlarged central longitudinal section through the holder; and

Fig. 4 is an end view of the device shown in Fig. 3.

It has been found that hypodermic needles will work best if sharpened on an angle of approximately 20° relative to the axis of the needle, and in order to achieve the best results the present invention provides a holder 10 which may be

2

knurled for a part of its length and which in the present case is illustrated as cylindrical. This holder is formed with a surface 12 at a 20° angle to the axis of the holder, providing a precision surface for guiding a stone or other grinding tool 14 which is reciprocated on the inclined surface as shown by the arrow in Fig. 1.

Fig. 1 also shows in dotted lines the needle 16, the penetrating end of which intersects surface 12 so as to be ground and honed according to the inclination of the surface.

As shown in Fig. 3, the holder 10 is hollowed out for a considerable portion of its length as indicated at 18 and terminates in an inclined shoulder 20. This shoulder merges with a tapered portion 22 which may have an approximately 2° taper. The tapered portion 22 which is shown as conical communicates with a passage 24 to accommodate the needle 16, passage 24 leading from the hollow portion 18 to the surface 12.

The hypodermic needle itself comprises the penetrating part 16, tapered portion 26 which fits the hollow taper 22, and a cap 28 which is hollow and interiorly cylindrical. All hypodermic needles are made in this fashion as is well known.

A rod 30 is provided, this rod having at one end a tapered projection 32 which receives the part 28 of the hypodermic needle and due to the taper of the projection 32, the hypodermic needle will be lightly but firmly held particularly if it is given a slight twisting motion when applied to the projection. The rod 30 is provided with a spring-pressed ball 34 which holds the rod 30 wherever it is placed in the hollow 18, and the opposite end of the rod 30 is provided with a knurled finger grip portion 36 for manipulating the same.

The passage 24 is made to accommodate the needle 16 as closely as possible and in actual practice passage 24 is made with a No. 72 drill, but, of course, this particular size may be varied to suit conditions although it is believed that 28 thousandths of an inch is the correct size for this passage.

It will be seen that this invention provides a compact tool which may be carried in the pocket or purse; it cannot get out of order inasmuch as the surface 12 is fixed and will not deteriorate regardless of the length of the use of the same. The hypodermic needle is firmly held in position and the light stoning will not disarrange the needle in any way so that a good sharp clean penetrating end is easily obtainable. The present device may be made of any kind of material

desired, metal, glass, plastic, or any suitable material without departing from the scope of the invention and it is pointed out that the device is so simple in the use and operation thereof that anyone can operate the same effectively in order to maintain the hypodermic needle in optimum condition.

The ball 34 is fully concealed when in use, and prevents any tendency to rotative or longitudinal movement of the rod 30, thus avoiding any and all screws, clamps, etc., and the taper 32 will take and hold all hypodermic needles made. In the use of the device both hands are used independently so that correct positioning is easily obtained, and the device cannot slip due to the generous knurling.

Having thus described my invention and the advantages thereof, I do not wish to be limited to the details herein disclosed otherwise than as set forth in the claims, but what I claim is:

1. A device for precision sharpening of hypodermic needles having tapered caps, comprising a body open at one end and closed at the other end, and hollow for a substantial part of its length, a small passage from the hollow through the closed end of the body, a slightly enlarged tapered portion at the end of the passage at the hollow, a flat inclined tool guiding surface at the closed end, said passage intersecting the surface, a rod in the body, said rod adapted to hold a hypodermic needle by the cap thereof, the needle being alined with the passage by the rod as the latter is slid into the hollow body, the tapered

cap being received and held in the tapered portion of the passage.

2. A device for sharpening hypodermic needles held in caps, comprising an elongated holder open at one end and closed at the other end, the holder having a generally cylindrical hollow therein from the open end inwardly, a shoulder at the inner end of the hollow, a central passage from the shoulder to the closed end, an inclined surface on the holder, the passage intersecting the surface, a cylindrical rod in the holder, said rod closely fitting the hollow, tapered means to secure a hypodermic needle to the rod, the latter being rotatable and axially slideable in the holder, means resisting movement of the rod in the holder, the cap of the hypodermic needle being adapted to abut the shoulder to hold the needle as close as possible to the penetrating end thereof.
